UNITED STATES PATENT OFFICE.

ELMER A. SPERRY, OF CLEVELAND, OHIO.

VALVE.

1,018,591.

Specification of Letters Patent. Patented Feb. 27, 1912.

Application filed February 21, 1895. Serial No. 539,298.

To all whom it may concern:

Be it known that I, ELMER A. SPERRY, a citizen of the United States, residing at Cleveland, in the county of Cuyahoga and State of Ohio, have invented certain new and useful Improvements in Valves, of which the following is a specification.

My invention relates to means for automatically preserving an effective action of valves, such as "puppet-valves," and it consists in a construction whereby a grinding of the valve parts on one another when the valve seats is accomplished by a greater or less amount of rotary motion which is imparted to the valve at suitable periods during its lifting action, preferably either while opening or closing, all of which is pointed out in the following specification, reference being had to the accompanying drawings, in which—

Figure 1 represents a sectional view of one form of device as applied to the valve; Figs. 2 and 3 represent the same form of device, wherein the action is rendered intermittent, with reference to the valve openings; Fig. 4 is a modification which represents a device for relieving the friction; Fig. 5 represents fully the details of another form of the structure; Fig. 6 is a detail of the valve-rotating device shown in Fig. 5.

Like letters of reference indicate like parts throughout the several views.

Referring now to Fig. 1, it will be seen that the casing C C contains the usual passageways of a puppet-valve, together with the valve opening containing seat a' against which rests the valve proper, a . The valve is supported and guided by a valve-stem B passing outward through the walls of the casing, as is usual in structures of this character. The valve-stem is provided with a head H which receives the thrust of the spring O by means of which the valve is normally held to its seat. The head H of the valve-stem will also be seen to be provided with ratchet-teeth t , which, in Fig. 5, are on the periphery of the head, whereas in the other figures, they are upon the crown of the head. Wherever these teeth may be located, they coöperate with the pawl P, seen in the act of engagement in Figs. 2 and 3, which in Fig. 5 passes behind the head H and which serves, by engagement of the teeth, to impart a rotary motion (more or less in extent) to the valve. It will furthermore be noticed that the pawl

P is operated, or has motion imparted to it, by a mechanism, which at the same time is associated with, or forms a part of, the valve-opening mechanism, so that the period of its movement bears some relation to the movement of the valve, the object being to impart a slight rotary movement to the valve, preferably at the time that it is either being lifted from the seat, or just before seating. Bearing this in mind, and referring now to Fig. 5, it will be seen that the valve-opening mechanism consists in a rocker-shaft R' and the rocker-arm R, which coöperates with the convex surface of the lever L, swinging upon the fulcrum L' and which, when depressed, forces the valve, head, stem and all, downwardly and off its seat, opening the valve. During this motion, it will be seen that the spring S is compressed, exerting its pressure against the head of the pawl P indicated at p and seen to the right, within the rectangular recess S'; the hook of the pawl, which is not seen, being behind the head H, is engaged with the teeth t of such head, and as soon as the pressure at the valve-seat has been sufficiently reduced by the downward pressure from the lever L, the pressure of the spring S, which is constantly increasing, is presently found sufficient to cause a movement of the pawl P and a corresponding slight rotation of the head H, stem B, and valve A. It will be noticed that at the time of this rotation, the valve is still in contact with its seat a' , although its pressure thereon has been materially decreased, but sufficient pressure still remains to effectually grind the surfaces or sweep them clear of any abrading substance.

Comparing the above outlined action with that of Figs. 1, 2 and 3, it will be seen that the corresponding parts are indicated by similar letters; *i. e.*, the pawl P, valve-stem B, teeth t , and valve-opening lever L are all present, but in somewhat altered form. The valve-opening lever L, swinging around its fulcrum, shown in Fig. 1, vibrates upward and downward over the valve-stem B, and is provided immediately above same with an abutting piece H', mounted on the stem H'' (see Fig. 3), provided with friction relieving balls G'. At the upper end, near the letter H'' will be seen a retaining pin, for preventing the downward movement of the stem with reference to the lever L. On an upward projection of the lever L near

2

this point, (Figs. 1 and 3), is provided a pivot D' , upon which is mounted a cam held thereon by nut D'' and provided at its periphery with means of effecting its rotation, 5 which, in the present instance, consists of ratchet-teeth, which coöperate with the dog G , mounted upon the stationary part (see Figs. 1 and 2) held by the pivot G' , and forced into engagement with the cam by 10 spring g . The pawl P in these figures is not mounted directly upon the valve-opening lever L , but is connected therewith by a link L'' , which is depressed forcibly by the spring S' . A pin suitably located upon this 15 link within the cam, and indicated at p' (Fig. 1), engages the slot r of the cam D , by means of which the link as a whole may be raised or lowered according to its position in the cam slot, which is provided with 20 one or more radial enlargements r' allowing the pin p' to descend with the link L'' whenever one of these is reached in course of the rotation of the cam D , this position being that shown in Figs. 2 and 3. At such 25 times the downward movement is sufficient to allow the pawl P to engage the teeth t , as indicated in these figures, but when the pin p' is in any other part of the cam slot, the link L'' and pawl P are raised so that the 30 link is entirely out of engagement with the teeth t , during all parts of the excursion of the lever L , as it descends in the act of pushing the valve-stem B downwardly and opening the valve. When however the link L'' 35 is in its lower position, the pawl P engages one of the teeth t , as the lever L descends toward the end of the valve-stem and prior to actual engagement between it and the abutment H' provided for the purpose, and 40 then during the remainder of the descending motion and before pressure is exerted upon the valve stem B , an upward movement is imparted through the engagement of the pawl with the teeth t to the link L'' , where- 45 by the spring S' is energized, which spring S' , acting through the parts, urges the pawl P to rotate the valve-stem B , through the teeth t , as soon as the descending pressure upon the valve-stem B has sufficiently relieved the friction at the valve-face, to allow 50 of such rotary movement. Upon each upward movement of the valve-operating lever L , carrying with it the cam-wheel D , the pawl G will engage a new tooth upon the 55 periphery of the cam and cause it in this manner to acquire, step by step, rotary motion. As this motion proceeds, the depression r' is finally turned from pin p' , which now finds itself in a small part of the slot 60 and the pawl P is raised clear from engagement with the teeth t . Thus it will be seen that a number of valve-openings will occur before the pawl P is again permitted to engage the teeth t , or any attempt at rotation 65 of the valve is made. This rotation, in case

of Figs. 1, 2 and 3, will be periodic, or with interrupted action, as compared with the valve-openings, whereas in Fig. 5 it will be seen that it occurs synchronously therewith. The grinding effect thus imparted to the valve is of especial value to give a clean, 70 bright seat and impart a constant tendency to clear itself from any collecting matter. It is especially serviceable where corrosive substances, gas and liquids, are handled at 75 high temperatures, which have a tendency to corrode the surfaces and soon render them leaky and unsuitable for use.

The operation has been so constantly referred to throughout the description, that 80 it will not require further special mention.

The word "lifting" is used in this specification and claims in the ordinary sense with which it is employed in connection with puppet valves and refers to the unseating or movement of the valve away from its seat regardless of the position in which the valve may at the moment stand.

Of course it will be readily understood that the valve casing may be of any style 90 or design and with other forms of construction and details of rotary mechanism, without departing from the spirit of the invention. Also other means may be employed for interrupting the action, and 95 while it is intended that all the principal features of the invention are to be employed and operated in connection with each other, yet some may be used without the others and the invention extends to such 100 use.

What I claim as new and desire to secure by Letters Patent of the United States is,

1. The combination of a lifting valve and 105 stem, a seat for the valve, means for raising the valve from its seat, a ratcheted head attached to said valve-stem, and a pawl connected to the reciprocating parts operating the valve, whereby when the said 110 valve is unseated a partial rotation is imparted to the same, substantially as specified.

2. The combination of a lifting valve and 115 stem, a seat for the valve, means for raising the said valve from its seat, means for partially rotating said valve during the operation of unseating, and means whereby 120 said partial rotation comes into operation during a portion only of the seatings and unseatings of the valve, substantially as specified.

3. The combination of a lifting valve and 125 stem, a seat for the valve, means for raising said valve from its seat, means for partially rotating said valve during the operation of unseating, means whereby said partial rotation comes into operation during a portion only of the seatings and unseatings of the valve, and mechanism whereby 130

the last named means is intermittently operated simultaneously with the seatings and unseatings of the valve, substantially as specified.

5. 4. The combination of a lifting valve and stem, a seating for the valve, means for raising the valve from its seat, means for partially rotating said valve while still engaging the seat, and an intermittently rotated cam, operated simultaneously with the seatings and unseatings of the valve, and coming periodically into operative communication with the said means for partially rotating the valve, substantially as specified.

15. 5. In combination, a valve seat, a valve held against the seat with considerable pressure when the valve is closed, means for moving the valve away from the seat to open it, and means for rotating the valve relative to the seat after the pressure between the valve and seat is diminished by the initial operation of the valve moving means, but before the valve has been moved 25 out of engagement with its seat.

30. 6. In combination with a lifting and rotating valve, a vibrating lifter for the valve, a spring for rotating the valve, and means whereby the spring is energized by the vibrations of the said lifter.

35. 7. In combination with a lifting and rotating valve, a vibrating lifter, means for rotating the valve, in combination with a spring imparting a yielding tension to the said means for rotating the valve, whereby rotation does not take effect until a portion of the pressure upon the valve-seat has been relieved.

40. 8. In combination, a rotating and lifting valve and its seat, means for subjecting the

valve to pressure upon its seat, means for partially removing such pressure and means for rotating the valve at the time of such partial removal of pressure and while the valve engages the seat.

45

9. In combination, a rotating and lifting valve and its seat, means for subjecting the valve to pressure upon its seat, a combined means for partially removing such pressure and for lifting and reseating the valve, and 50 means for rotating the valve at the time of such partial removal of pressure and while the valve engages the seat.

10. In combination, a rotating and lifting valve and its seat, means for subjecting the 55 valve to pressure upon its seat, means for partially removing such pressure and a resilient means for rotating the valve at the time of such partial removal of pressure and while the valve engages the seat.

60

11. In combination, a rotating and lifting valve and its seat, means for subjecting the valve to pressure upon its seat, means for partially removing such pressure and means for periodically rotating the valve, the said 65 period made to occur at the time of the said partial removal of pressure and while the valve engages the seat.

12. In combination with a lifting and rotating valve a vibrating lifter, means for 70 rotating the valve in combination with intermediate mechanism whereby the rotation takes effect only after a portion of the pressure upon the valve seat has been relieved and while the valve still engages the 75 seat.
